UNITED STATES PATENT OFFICE

149,129

DESIGN FOR A TRUNDLE TOY OR
SIMILAR ARTICLE

Benjamin Katz, New York, N. Y.

Application July 2, 1946, Serial No. 131,272

Term of patent 3½ years

(Cl. D34—15)

To all whom it may concern:

Be it known that I, Benjamin Katz, a citizen of the United States of America and a resident of the Borough of Manhattan, city, county, and State of New York, have invented a new, original, and ornamental Design for a Trundle Toy or Similar Article, of which the following is a specification, reference being had to the accompanying drawings, forming a part thereof, in which

Figure 1 is a side elevational view of a trundle toy, showing my new design;

Fig. 2 is a rear elevational view thereof with parts broken away for convenience of illustration;

Fig. 3 is a sectional view on the line 3—3 of Fig. 2;

Fig. 4 is a sectional view on the line 4—4 of Fig. 1;

Fig. 5 is a perspective view of the trundle toy showing my new design.

I claim:

The ornamental design for a trundle toy or similar article, as shown.

BENJAMIN KATZ.
